No. 36,438.

Patented July 14, 1903.

UNITED STATES PATENT OFFICE.

MURRAY R. BOTKIN, OF KOKOMO, COLORADO.

DESIGN FOR A DISPLAY-RACK.

SPECIFICATION forming part of Design No. 36,438, dated July 14, 1903.

Application filed August 7, 1902. Serial No. 118,833. Term of patent 7 years.

To all whom it may concern:

Be it known that I, MURRAY R. BOTKIN, a citizen of the United States, residing at Kokomo, in the county of Summit and State of Colorado, have invented and produced a new, original, and ornamental Design for a Display-Rack, of which the following is a specification.

This invention relates to a new, original, and ornamental design for a display-rack, and the figure of the drawing is a perspective view of a display-rack, showing my new, original, and ornamental design.

What I claim is—

The ornamental design for a display-rack, as herein shown.

In testimony that I claim the foregoing as my own I have hereto affixed my signature in the presence of two witnesses.

MURRAY R. BOTKIN.
